Primary Examiner — Elizabeth J Oswecki*(74) Attorney, Agent, or Firm* — Greenblum & Bernstein, P.L.C.(57) **CLAIM**

I claim the ornamental design for a visor for helmets, as shown and described.

DESCRIPTION

FIG. 1 is a front perspective view of a visor for helmets, showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is another front perspective view thereof shown in a used condition with a helmet shown in broken lines.

Any surfaces of the design not shown, including any surfaces shown in broken lines, form no part of the claimed invention.
